UNITED STATES PATENT OFFICE.

SARAH A. GRAFFUNDER, OF TACOMA, WASHINGTON, ASSIGNOR TO HOME GAS APPLIANCE CO., OF TACOMA, WASHINGTON, A CORPORATION OF WASHINGTON.

OIL-BURNER.

1,341,797.

Specification of Letters Patent. Patented June 1, 1920.

Application filed July 11, 1919. Serial No. 310,112.

To all whom it may concern:

Be it known that I, SARAH A. GRAFFUNDER, a citizen of the United States, and resident of the city of Tacoma, county of Pierce, and State of Washington, have invented certain new and useful Improvements in Oil-Burners, of which the following is a specification.

This invention relates to new and useful 10 improvements in oil burners, and more particularly, kerosene oil burners used in heating the cooking stove, and the object of this improvement is to provide an oil burner that can be manufactured cheaply, of a simple 15 design, and durable form of construction, that will not quickly deteriorate under excessive heat.

A further object resides in the arrangement and construction of the burner where- 20 in the ports for supplying air to the jet of oil are so arranged with respect to the oil port, that the air will be drawn across the oil jet and unite therewith to form a proper mixture at a point midway between 25 the ports and a baffle plate, against which the flame is deflected.

A further object resides in the arrangement of a drain for directing the oil that may escape from the oil port, in event the 30 flame becomes extinguished, into a receptacle or basin, which is formed integral with the burner, and thus preclude leakage into the ash-box.

A further object resides in the provision 35 of means for rendering accessible the interior of the burner for easy cleansing of the scale that accumulates therein, and for keeping the port, where the oil is released to the atmosphere, from becoming clogged.

40 A still further object resides in the form of construction and means of mounting a baffle plate for controlling the manner in which the flame can be deflected.

The invention consists in the arrange- 45 ment, construction and combination of parts as will be more fully described in the following specification, illustrated in the accompanying drawings, and finally pointed out in the appended claims.

50 In the drawings,

Figure 1 is a perspective view of my im- 55 proved burner, as applied to a kitchen range.

Fig. 2 is an enlarged view of the same 58 detached from the range.

Fig. 3 is a vertical section taken on line 3—3 of Fig. 4.

Fig. 4 is a horizontal section taken on line 4—4 of Fig. 3.

Referring more particularly to the drawings, in which like reference numerals indicate like parts, the numeral 1 represents an ordinary kitchen range comprising a fire box 2, into which my burner is applied. The base 3 of the burner is preferably embedded 60 in a layer of asbestos 4, or other noninflammable material, which covers the bottom of the fire grate, so as to preclude any air from passage around the base of the burner.

This base 3, as herein shown, is formed with a guard 5 upon its outer sides, forming 70 a basin 14 to retain any overflow of oil that may escape from the port 6 of the burner. This burner consists simply of a hollow, elongated-shaped member 7, that is formed integral with the base 3, having its 75 ends tapped for the reception of plugs 8.

The port 6, provided in the top of the burner, communicates with the hollow center, and in alinement with this port is a cleaner 9 having a needle point 10 that ex- 80 tends up through the hollow of the member 7, and is adapted to be projected through the port 6 and cleanse the same of any foreign substance that may accumulate 85 and preclude the passage of oil there- through.

The member 7 is further formed with shoulders 11 on both sides of the port 6, that are provided with elongated passageways 12 that extend through the base 3 and are open 90 at both ends to the atmosphere. Depres- 95 sions, or troughs 13, are formed in the shoul- ders 11, on both sides of the member 6 to drain off the oil in the basin 14, that escapes from the port 6, should the flame become 95 extinguished and thus preclude leakage into the ash pan of the stove, where it may become ignited and develop into serious con- sequences.

Secured to the member 7, at one end, is a 100 feed pipe 15 that registers with the hollow center of the member. This feed pipe 15 is adapted to be coiled over the top of the burner and thence extend to and connect with the oil reservoir 16, placed at some 105 convenient place out of the way.

17 is a baffle plate that is both slidably and rotatably disposed upon the pipe 15,

centrally the coil, and this baffle plate is preferably concaved on one side and convexed on the other, the weight being equally distributed with respect to its pivot point, 5 so that the plate will remain stationary irrespective of the position at which it may be tilted.

It is obvious that by simply reversing the 10 faces of this baffle plate the flame can be projected downwardly or upwardly, or by tilting or sliding it longitudinally upon the pipe 15, the flame can be deflected to either side, as desired.

The novel construction and adaptation of 15 this baffle plate as a deflector serves the further function in that it can be built of sufficient cross sectional area to throw off considerable heat by radiation.

Having thus described my invention, what 20 I claim as new and desire to protect by Letters Patent, is:

1. An oil burner of the class described comprising a base plate having a conduit formed integral therewith, a port in the 25 upper side of said conduit, a feed pipe connected to said conduit and with an oil reservoir whereby oil can be delivered to said conduit and be ejected outwardly through said port and means for supplying air 30 through said base on both sides of said conduit opposite said port to form a proper mixture with said oil, and a baffle plate rotatably disposed upon said feed pipe above said port having its opposite faces convexed 35 and concaved respectively and adapted to be caused to assume any tiltable position for deflecting the flame of said burner.

2. An oil burner comprising a base plate having a conduit formed integral therewith, 40 a port in the upper side of said conduit, a feed pipe connecting with said conduit and

coiled upwardly over said port and thence extended to and connected with an oil reservoir whereby oil can be delivered to said conduit and be ejected outwardly through 45 said port, shoulders provided on the opposite sides of said conduit having slots extended downwardly through said base plate for supplying the proper quantity of air to the jet of oil passing outwardly through 50 said port, and means mounted upon said feed pipe above said port for deflecting the flame that is projected thereagainst in any direction.

3. An oil burner comprising a base having 55 a basin formed in its upper side, a conduit formed integral with said base, a port in the upper side of said conduit, means provided on the ends of said conduit for rendering accessible the interior thereof for cleansing, 60 means provided on the bottom of said plate adapted to be projected upwardly through said port for cleansing, shoulders formed integral with said conduit on both sides thereof adjacent said port having slots extending downwardly through said base, channelways provided on the top of said shoulders at their juncture with said conduit, a feed pipe connecting at one end with said conduit and coiled over the top of said 65 port and thence extended to and connected with an oil reservoir, and a member rotatably mounted upon said feed pipe above said port having its opposite sides convexed and concaved respectively and adapted to 70 remain stationary in any tiltable position whereby the flame may be deflected in any direction.

Signed at Tacoma, Washington, this 19th day of February, 1919.

SARAH A. GRAFFUNDER.
